PROCESS FOR PRODUCTION OF γ LACTONES

Georg Scheuing and Brune Walach, Nieder-
Ingelheim-on-the-Rhine, Germany, assignors
to C. H. Boehringer Sohn Aktiengesellschaft,
Nieder-Ingelheim-on-the-Rhine, Germany, a
corporation of Germany

No Drawing. Application May 11, 1931, Serial
No. 536,652. In Germany May 17, 1930

10 Claims. (Cl. 260—123)

This invention relates to a process for the production of hydro-aromatic γ -lactones. γ -Lactones are of importance, because many of them occur in nature as physiologically active substances, thus for example, santonin contains the γ -lactone group. Thus, for example, also the action of santonin on intestinal parasites has been ascribed to its lactone group. Simple γ -lactones, such as, for example, phthalides, were indeed also examined for their anthelmintic action. They have, however, been found to be of no therapeutic importance.

By an exhaustive investigation it has now been found according to this invention that γ -lactones possessing a santonin-like action and having the general formula

(wherein R_1 represents hydrogen or alkyl, R_2 and R_3 carbon radicals which are closed up into hydroaromatic ring systems) can be produced by heating beta-hydroxy-acid esters of the type

(wherein R_1 , R_2 and R_3 have the same meaning as in Formula I, R_4 is an alkyl group) with mineral acids such as, for example, sulphuric acid or hydrobromic acid.

The beta-hydroxy-acid esters of the type II serving as the initial material, may be obtained in known manner according to the Reformatsky synthesis from halogen fatty acid esters, ketones such as, for example, those with hydro-aromatic six membered rings and zinc.

For example, in carrying the invention into effect alpha-(1-hydroxycyclohexyl-1)-fatty acid ester, prepared according to Reformatsky for example from cyclohexanone, alpha-halogen fatty acid ester and zinc, is converted by warming with mineral acid into the γ -lactone of alpha-(2-hydroxycyclohexyl-1)-fatty acid.

Further investigations have shown that it is possible in the same way to convert beta-hydroxy-acid esters which can be obtained, for example, from 2-keto-decahydronaphthalene, alpha-halo-

gen fatty acid esters and zinc and which possess the structure

III

(wherein R_1 represents hydrogen or alkyl, and R_4 represents alkyl) into lactones of the type

IV

The γ -lactones of decahydronaphthalene so obtained are particularly close to santonin in their constitution.

In the conversion of the said beta-hydroxy-acid esters into the γ -lactones according to this invention, the esters are probably first converted by a splitting out of water into the unsaturated esters and thereafter these are saponified into the beta- γ -unsaturated acids, which by again adding on water are converted into the γ -hydroxy-acids which can then undergo lactone formation. Quite possibly the individual reaction stages are passed through in other sequences or also take place side by side.

Instead of converting the beta-hydroxy-acid ester into the lactone direct by treatment with mineral acid in the warm, the reaction can be effected in stages for example so that the beta-hydroxy-acid ester is converted by water splitting-out agents into the unsaturated ester which, by saponification, is converted into the free acid and ultimately by treatment with mineral acid in the warm, into the lactone.

The concentration of the acid employed for the lactonization depends upon the solubility of the beta-hydroxy-acid ester employed, and in particular upon the reaction temperature. At the boiling temperature, for example, a moderately concentrated sulphuric acid of about 50–60%, suffices for complete lactonization, whereas at 50–60° C. it is necessary to employ an 80–85% sulphuric acid. In like manner also if other acids, for example, hydrobromic acid, are employed, higher treatment temperatures are necessitated by lower concentrations of acid.

The lactones obtained according to the invention are insoluble in soda and ammonia, are split up by lyes and then yield on acidification the corresponding gamma-hydroxy-acid. The gamma-lactones can be regenerated therefrom, whereby these compounds are recognized as analogues of the already known gamma-lactones.

The conversions according to the present invention are illustrated by way of example by the following structural formulæ:—

The gamma-lactones obtained according to the process of the present invention may be employed as agents against animal parasites, for example as anthelmintics; and as agents for destroying noxious pests and the like.

Compounds possessing a constitution like santonin have indeed already been produced, but according to the known processes, for example by double decomposition of alpha-halogen ketones with sodium malonic ester whereby the difficultly isolatable gamma-ketomalonic acid is first produced, which by reduction of the carbonyl group, splitting out of carbon dioxide and lactonization may be converted into the desired product. In contrast to these troublesome processes, the process according to the present invention provides the gamma-lactones of the kind hereinbefore described easily and in a form in which they can be simply isolated.

Examples

1. 76 grams of 2-keto-decahydronaphthalene ($=\frac{1}{2}$ mol.) are decomposed with about 50 grams of zinc borings and 84 grams of alpha-bromopropionic acid methyl ester ($=\frac{1}{2}$ mol.) in a benzene-ether solution according to Reformatsky. There are obtained 110 grams (92% of the theoretical) of alpha-(2-hydroxydecahydronaphthyl-2)-propionic acid methyl ester of boiling point 128° C./0.6 mm. By treatment with water splitting out agents there are obtained from 110 grams of this hydroxy-ester by a lengthy distillation with about 70 grams of potassium bisulphite, 95 grams (93% of the theoretical) of alpha-(octahydro-naphthyl-2)-propionic acid methyl ester of boiling point 145° C./13 mm. By saponification with aqueous-alcoholic alkali there are obtained 85 grams (95% of theory) of alpha-octahydro-naphthyl-2-propionic acid of boiling point 143° C./0.9 mm.

85 grams alpha-octahydronaphthyl-2-propionic acid are mixed with 200 ccs. of 70% sulphuric acid and the clear solution warmed gently for some time, whereby lactonization takes place under slight self-warming. The solution thereby becomes turbid and after dilution with ice the lactone which has separated is shaken out with ether or benzene and the ether or benzene solution removed from the almost non-lactonizing acid by washing with dilute soda solution. 77 10

grams (90% of the theoretical) of the gamma-lactone of alpha-(1-hydroxy-decahydronaphthyl-2)-alpha-methyl-acetic acid of boiling point 145° C./0.6 mm. are obtained.

If the above-mentioned hydroxy acid ester or unsaturated ester are treated under like conditions with 70% sulphuric acid, there is likewise obtained the gamma-lactone described. The gamma-lactone is sparingly soluble in water, whereas it is easily soluble in almost all organic solvents. The barium salt of the corresponding hydroxy-acid alpha-(1-hydroxy-2-deca-hydro-naphthyl)-alpha-methyl acetic acid of boiling point 153° C./0.9 mm. can be obtained from the gamma-lactone by saponification with barium hydroxide. By treatment with acid the original gamma-lactone can be regenerated. The structural formula may be expressed as follows:—

2. 75 grams of alpha-(1-hydroxycyclohexyl-1)-butyric acid methyl ester (cf. Wallach, Annalen vol. 360, pages 44-81) are dissolved in 300 ccs. of 70% sulphuric acid under gentle warming. After some time the solution becomes turbid with a slight darkening of the colour. After an hour it is entered into ice. The oil which separates out is taken up in benzene, the benzene solution is washed with soda and dried. The residue from the benzene solution distils at 15 mms. between 141-145-147° C. There are obtained 53 grams of the gamma-lactone of alpha-(2-hydroxycyclohexyl-1)-butyric acid.

The product has the following formula:

The lactone is insoluble in soda and ammonia but in the presence of some alcohol is easily converted by barium hydroxide into the salt of alpha (cyclohexanol-2)-butyric acid. This boils under 5 0.6 mm. pressure at 108° C. and is easily further converted by mineral acids back into the lactone.

Under like conditions the alpha-(Δ ,1-cyclohexenyl-1)-butyric acid methyl ester is converted into the lactone. This ester is obtained by introducing the above-mentioned beta-hydroxy-acid ester into a four-fold quantity of 70% sulphuric acid in which a raising of the temperature above 10 30° C. must be avoided. Thereby there first arises a clear solution which becomes turbid by 15 the separation of oil. The alpha-(Δ ,1-cyclohexenyl-1)-butyric acid methyl ester which is insoluble in water is isolated in the usual manner. Its boiling point at 11 mm. is 105° C. The product has the following formula:

3. 70 grams of alpha-(1-hydroxycyclohexyl-1)-acetic acid methyl ester (0.4 mol.) is allowed to flow into 250 ccs. of gently boiling 40% hydrobromic acid. Splitting out of water, saponification of the ester and lactonization take place with evolution of methyl bromide. By employing concentrated hydrobromic acid (50-60%) a temperature of 50-60° C., suffices for effecting the reaction. When the evolution of methyl bromide subsides the lactonization is complete. There is obtained 42 grams of an oil of boiling point 130° C./12 mm. which is insoluble in sodium carbonate. The yield is 75% of the theoretical. The purity of the product is demonstrated by treating it with barium hydroxide and splitting out water from the gamma-hydroxy-acid by warming with dilute sulphuric acid and thus converting it back 40 again into the lactone. The yield is 40 grams (=95% of the theoretical) and the boiling point 130° C./12 mm. The lactone of the alpha-(2-hydroxycyclohexyl-1)-acetic acid (=gamma-lactone of α -hydroxyhexahydrophenyl acetic acid) is very easily soluble in organic solvents, is 45 appreciably soluble in water and possesses the characteristic lactone odour. The corresponding gamma-hydroxy-acid is almost insoluble in benzene. The product has the following formula:

4. 93 grams of alpha-(1-hydroxycyclohexyl-1)-propionic acid methyl ester ($\frac{1}{2}$ mol.) is introduced into 300 ccs. of gently boiling 50% sulphuric acid under stirring. After a short period of warming the solution is diluted and the lactone taken up in benzene. The yield of the lactone which is insoluble in sodium carbonate amounts to 53 grams (82% of the theoretical) of 60 boiling point 130° C./11mm. After conversion with baryta to the gamma-hydroxy acid and again lactonizing 61 grams of gamma-lactone of the alpha-(2-hydroxycyclohexyl-1)-propionic acid are obtained (=97% of the theoretical).

The boiling point is 130° C./11mm. The product has the following formula:

5. 93 grams of alpha-(1-hydroxycyclohexyl-1)-propionic acid methyl ester ($\frac{1}{2}$ mol.) are dissolved at 60-70° C. in 200 ccs. of 85% sulphuric acid, after a short time the solution is diluted and worked up as in Example 4. The yield is 71 15 grams (92% of the theoretical) of gamma-lactone of the alpha-(2-hydroxycyclohexyl-1)-propionic acid. The boiling point is 130° C./10 mm. The product has the following formula:

What we claim is:

1. A process for the direct production of gamma-lactones of the general formula, Type I,

wherein R_1 represents a member of the group consisting of hydrogen and alkyl, and R_2 and R_3 represent carbon radicals which are closed up jointly into hydroaromatic ring systems of not more than two rings which comprises heating in the presence of a non-oxidizing, strong mineral acid, beta-hydroxy acid esters of the general formula, Type II,

wherein R_1 to R_3 have the same meaning as in Formula I and R_4 is an alkyl group to effect their conversion into gamma-lactones of the aforesaid type.

2. A process as claimed in claim 1, wherein the beta-hydroxy acid esters of the Type II are converted by stages into the desired lactones by first converting them into the corresponding beta-gamma unsaturated acid esters by means of water removing agents, saponifying these and converting the acids obtained into gamma-lactones by heating with non-oxidizing, strong mineral acids.

3. A process as claimed in claim 1, wherein the higher the treatment temperature the lower is the concentration of acid employed.

4. A process as claimed in claim 1, wherein the lactonization is effected with sulphuric acid.

5. A process as claimed in claim 1, wherein the substituents R_2 and R_3 of the general Formula II are closed up into a hexahydro-benzene ring so that alpha-(1-hydroxycyclohexyl-1) lower fatty acid ester is converted into the gamma lactone of alpha-(2-hydroxycyclohexyl-1) lower fatty acid.

6. A process as claimed in claim 1, wherein the substituents R_2 and R_3 of the general Formula II

are closed up into a decahydronaphthalene ring so that gamma-hydroxy acid esters of the type

are converted into -lactones of the type

by heating with non-oxidizing, strong mineral acids.

7. As a new compound, gamma-lactone having the general formula:

wherein R₁ represents an alkyl, R₂ and R₃ represent carbon radicals which are closed up jointly into hydroaromatic ring systems of not more than two rings.

8. As a new compound the gamma-lactone of alpha-(1-hydroxydecahydronaphthyl-2)-alpha-methyl-acetic acid having the following formula:

9. As a new compound the gamma-lactone of the alpha-(2-hydroxycyclohexyl-1)-propionic acid having the following formula.

10. As a new compound gamma-lactone of the alpha-(2-hydroxycyclohexyl-1)-butyric acid having the following formula:

GEORG SCHEUING.
BRUNO WALACH.
